UNITED STATES PATENT OFFICE.

GEORGE THOMPSON, OF MOUNT VERNON, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed February 9, 1924. Serial No. 691,557.

To all whom it may concern:

Be it known that I, GEORGE THOMPSON, a citizen of the United States of America, residing at Mount Vernon, in the county of 5 Westchester and State of New York, have invented certain new and useful Improvements in Telephone-Exchange Systems, of which the following is a full, clear, concise, and exact description.

10 This invention relates to telephone exchange systems and more particularly to systems in which connections are established by means of automatic switches.

15 Telephone systems employing automatic switches are so arranged that under normal conditions it is impossible to connect with a busy line, the final selector, which has access to subscribers' lines, being caused to test whether the line is idle or busy and to release and transmit a signal when the called line is busy.

20 For various reasons it is sometimes desirable to permit the operator to connect with a line which repeatedly tests busy. This 25 has been accomplished in a variety of ways, usually by means of what is known as a "no test" key. In systems in which final selectors are employed which release under the control of the calling subscriber, the 30 key control method of connecting with a busy line is entirely satisfactory. It has been found however that, in the case of final selectors which await restoration of the 35 called line before releasing, a tie-up may result when the operator releases her end of the "no-test" connection. This tie-up may be between the final selector used in establishing the normal call and the final selector used "no-test," or if the busy line is a calling 40 line, it may be between the district selector with which the subscriber's line is connected and the final selector used "no-test." Even where no tie-up occurs, transmission is frequently interfered with. This is, of 45 course, undesirable.

It is an object of the present invention to provide improved means for permitting connection to a busy line.

50 A feature of the invention lies in the provision of special incoming selectors at an operator's position for use in establish-

ing "no-test" connections with a subscriber's line.

Another feature of the invention lies in the provision of means for preventing the 55 release of said incoming selectors until the subscriber's line is returned to normal.

A further features of the invention lies in making the above mentioned release preventing means operative regardless of the 60 condition of the called line.

These and other features of the invention will be more clearly understood from a consideration of the following description in connection with the accompanying drawings and appended claims.

In the drawings, Fig. 1 shows an incoming selector circuit embodying the present invention. A calling subscriber's substation and the connection of that substation 70 to said incoming selector through an operator's position is indicated diagrammatically.

Fig. 2 shows a final selector of the type which awaits the restoration of the called 75 line before releasing.

It will be assumed that a connection has been established between substation 100 and substation 200 by means of line switch 101, district selector 102, incoming selector 103 80 and final selector 201. Suppose now that conversation over this connection continues for a considerable time and in the meantime, a subscriber located at substation 110 attempts a connection with substation 200 a 85 number or times, receiving each time a signal that the wanted line is busy. This subscriber may have reason to feel that this condition is abnormal and he may then connect with an operator's position by means 90 of line switch 111 and district selector 112 under the control of register sender 113. The trunk leading to the operator's position ends in jack 114 where a signal (not shown) will be displayed before the operator. The 95 operator answers the call by inserting a plug in jack 114 and ascertains what is wanted.

She may attempt connection with the desired line and, also receiving a busy signal, will then request of the B operator over 100 an order wire (not shown) a "no-test" connection with substation 200. The B operator

will assign a "no-test" trunk terminating at the first or intercepted operator's position in jack 116 and appearing at the B operator's position in keys 119 and 166. The 5 B operator will then depress assignment key 119, individual to the trunk and will set up the number of the called subscriber on her keyboard. The operation of assignment key 119 closes a circuit from battery 10 through the winding of incoming selector sequence switch magnet 120, lower right contact of cam 121, lower contacts of key 119 to ground. Magnet 120 operates in this 15 circuit and advances the sequence switch to position 2.

In position 2, ground is connected from the right contact of cam 130, through the outer back contact of relay 125, lower right contact of cam 131 to conductor 129 causing 20 the sender selector to operate and connect an idle cordless sender with the assigned trunk. Reference may be made to Patent No. 1,403,862 to A. E. Lundell, granted January 17, 1922, for a complete disclosure 25 of the operation of such a sender selector and sender in connection with a cordless or B operator's position. When these operations have been completed, ground is connected to conductor 132, and thence over the 30 lower left contact of cam 133, through the winding of sequence switch magnet 120 to battery. Magnet 120 operates in this circuit and advances the sequence switch to position 3. When the sequence switch 35 reaches position $2\frac{3}{4}$, ground is connected over the upper right and lower left contacts of cam 171 to conductor 172 to hold the selected sender.

When the intercepted operator inserts 40 plug 118 in jack 116 a circuit is completed for relay 122 and that relay operates. If the cordless operator has not depressed the assignment key and the sequence switch stands in position 1, a circuit is completed 45 from ground at the front contact of relay 122, upper left contact of cam 123, lower left contact of cam 124, left winding of relay 125 to battery. Relay 125 operates and closes a circuit from battery through 50 lamp 126, right contacts of cam 127, inner front contact of relay 125, lower contacts of cam 128 to ground. Lamp 126 lights to indicate that the trunk has been seized by the intercepted operator. When sequence 55 switch 120 leaves position 1 following the depression of assignment key 119, the above traced circuit for relay 125 is opened at cam 123 and that relay releases. In position 60 2 a circuit for lamp 126 is closed through the lower contacts of cam 130.

In position 3 the circuit for lamp 126 is extended over the lower right and upper left contacts of cam 127 and contact of interrupter 135 to ground. A circuit is also 65 closed from battery through lamp 134 and

the left contacts of cam 127 to the contact of interrupter 135 and ground. These lamps are lighted intermittently in this circuit and continue to flash until selection is completed.

Meanwhile the sender has been operating to register the designation set up on the operator's keyboard in the manner described in the above identified Patent No. 1,403,862, and, when registration is completed, ground 70 is connected to conductor 136 completing a fundamental circuit through the upper right contact of cam 123, lower left contact of cam 124, left winding of relay 125 to battery. Relay 125 operates in this circuit and completes a circuit from battery through the winding of sequence switch magnet 120, upper left contact of cam 121, outer front contact of relay 125, lower right contact of cam 130 to ground. Magnet 120 operates in this circuit and advances the sequence switch to position 5. 75

When the sequence switch reaches position 5, the energizing circuit previously traced for relay 125 is opened, but relay 125 is held operated in a locking circuit closed in position 4 from battery through the left winding of relay 125, upper right and lower left contact of cam 137, inner front contact of relay 125, lower left and upper right contacts of cam 123, conductor 136 and thence to ground through the stepping relay of the sender. In position 5 the circuit of updrive magnet 138 is completed from battery, through the winding of magnet 138, right contacts of cam 139, outer front contact of relay 125, lower right contact of cam 130 to ground. Under the control of magnet 138, the brush rod of selector switch 150 is moved upward in its brush selecting movement. As the selector brush rod moves upward commutator brush 140 engages conducting segments of commutator strip 141 and a circuit is completed from battery through the left winding of relay 125, the upper right and lower left contacts of cam 137, inner front contact of relay 125, lower left contact of cam 123, upper right contact of cam 124, commutator strip 141, brush 140, upper right contact of cam 142 to ground. Each time that a conducting segment is engaged by brush 140, this circuit holds relay 125 operated and shunts the stepping relay of the sender in the well known manner. When the stepping relay has been deenergized a number of times sufficient to satisfy the setting of the sender, the fundamental circuit above traced is opened and when brush 140 encounters an insulating segment of strip 141, relay 125 deenergizes. The deenergization of relay 125 opens the circuit of updrive magnet 138 and the selector comes to rest in position to trip the selected set of brushes. The deenergization of relay 125 100

also closes a circuit extending from battery through the winding of sequence switch magnet 120, lower left contact of cam 121, outer back contact of relay 125, right contact of cam 130 to ground. Magnet 120 operates and advances the sequence switch into position 6.

In position 6 the circuit of trip magnet 143 is closed from battery, winding of that magnet, upper right contact of cam 142 to ground. The fundamental circuit including relay 125 is again completed from battery through the left winding of relay 125, lower left contact of cam 124, upper right contact of cam 123, conductor 136 and thence through the stepping relay of the sender to ground. Relay 125 operates and locks in a circuit extending from battery through the left winding of relay 125, upper right and lower left contacts of cam 137, inner front contact of relay 125, lower left and upper right contacts of cam 123 and thence to ground as above traced. The operation of relay 125 closes a circuit from battery through the winding of sequence switch magnet 120, upper left contact of cam 121, outer front contact of relay 125, lower right contact of cam 130 to battery. Magnet 120 operates in this circuit and advances the sequence switch to position 7.

In position 7 the circuit of updrive magnet 138 is again closed from battery through the winding of that magnet, right contacts of cam 139, outer front contact of relay 125 to ground at the right contact of cam 130. The trip magnet 143 is operated at this time and the selected set of brushes will be tripped as the brush rod moves upward under the control of updrive magnet 138 in its group selecting operation. As the selector brush rod moves upward, brush 144 passes over conducting segments of commutator strip 145 and intermittently closes a circuit from battery through the left winding of relay 125, upper right and lower left contacts of cam 137, inner front contact of relay 125, lower left contact of cam 123, upper left contact of cam 124, commutator strip 145, brush 144, upper left contact of cam 142 to ground. At each closure of this circuit the stepping relay of the sender is shunted in the well known manner, and when the sender has been satisfied, the fundamental circuit above traced is opened. On the engagement of the next insulating segment of commutator strip 145 by brush 144, relay 125 deenergizes opening the circuit of updrive magnet 138 and bringing the selector switch to rest on the lowest terminal of the selected group. The release of relay 125 also closes a circuit from battery through the winding of sequence switch magnet 120, lower left contact of cam 121, outer back contact of relay 125, lower right contact of cam 130 to ground. Magnet 120

operates in this circuit and advances the sequence switch to position 8.

In position 8 a local circuit is closed for relay 125 extending from battery through the right winding of the relay upper left and lower right contacts of cam 128 to ground. Relay 125 operates and closes a circuit from battery through the winding of sequence switch magnet 120, upper left contact of cam 121, outer front contact of relay 125, lower right contact of cam 130 to ground. Magnet 120 operates and advances the sequence switch to position 9. If the first trunk of the group on which the selector switch 150 has come to rest is idle, relay 125 will release as soon as the sequence switch leaves position 8 $\frac{1}{4}$. If the first trunk is busy, ground will be present on the sleeve terminal thereof and a circuit will be completed from battery through the left winding of relay 125, lower left contact of cam 124, lower left contact of cam 123, inner front contact of relay 125, lower contacts of cam 137, sleeve brush 147, to ground on the sleeve terminal of a busy trunk. Relay 125 will be maintained energized. When the sequence switch arrives in position 9, the circuit of magnet 138 is again closed and the selector switch continues upward in its trunk hunting operation. Relay 125 is held operated as the selector passes from trunk to trunk over a circuit extending from battery through the right winding of relay 125, upper contacts of cam 128, commutator strip 148, commutator brush 149, upper contacts of cam 139, outer front contact of relay 125, lower right contact of cam 130 to ground. When an idle trunk is found no ground will be present on the sleeve terminal thereof and the circuit through the left winding of relay 125 will be opened; and when commutator brush 149 engages an insulating segment of strip 148 the circuit through the right winding of relay 125 will be opened and that relay will release. The release of relay 125 opens the circuit of updrive magnet 138 bringing the selector switch to rest on the terminals corresponding to an idle trunk. The release of relay 125 closes a circuit from battery through the winding of sequence switch magnet 120, lower left contact of cam 121, outer back contact of relay 125, lower right contact of cam 130, to ground. Magnet 120 operates and advances the sequence switch to position 11 in which position it remains during the operation of final selector 250. When the sequence switch reaches position 10, ground is connected to sleeve brush 147 over the upper left and lower right contacts of cam 137, for the purpose of making the selected trunk busy to all other selectors.

When the incoming selector sequence switch reaches position 11 a fundamental circuit is completed from battery through

the right winding of relay 203, upper right contact of cam 204, upper left contact of cam 205, over the tip side of the trunk to terminal 151, brush 152, lower right and 5 upper left contacts of cam 153, conductor 136, and thence through the stepping relay of the sender to ground. Relay 203 operates and locks in a circuit from battery, through the right winding of that relay, upper left contact of cam 211, right front contact of relay 203, upper left contact of cam 204, upper left contact of cam 205, and thence over the fundamental circuit previously traced to ground. The operation of 10 relay 203 closes a circuit extending from battery, left winding of relay 206, lower left contact of cam 207, left front contact of relay 203, lower left contact of cam 208 to ground. Relay 206 operates and locks in a circuit 15 through the back contact of relay 223 and the left front contact of relay 206 to ground on sleeve brush 147. The operation of relay 206 closes a circuit from battery through the winding of sequence switch magnet 209, lower contacts of cam 210, right front contact of relay 206 to ground. Magnet 209 20 operates and advances the sequence switch to position 2.

In position 2 relay 203 is held operated in 25 the above traced locking circuit, and the circuit of high speed updrive magnet 212 is closed from battery through the winding of that magnet, upper right contact of cam 213, left front contact of relay 203, lower left contact of cam 208 to ground. The brush rod of selector 250 is elevated at high speed 30 under the control of this magnet in its brush selecting movement. A circuit is momentarily completed from battery through the right winding of relay 203, upper right contact of cam 211, right front contact of relay 203, upper left and lower right contacts of cam 204, commutator strip 217, brush 218, upper left contact of cam 207, left front contact of relay 203, lower left contact of cam 208 to ground 35 each time brush 218 encounters a conducting segment of strip 217. The stepping relay of the sender is intermittently shunted and when this has been done a sufficient number of times the fundamental circuit is opened. When brush 218 engages the next 40 insulating segment in strip 217, the holding circuit of relay 203 is opened and that relay deenergizes. The deenergization of relay 203 opens the circuit of updrive magnet 212, and brings the selector to rest with the 45 brushes engaging the first terminals of the selected group. The release of relay 203 also closes a circuit from battery, winding of sequence switch magnet 209, upper right contact of cam 216, left back contact of relay 203, lower left contact of cam 208 to ground. Magnet 209 50 operates and advances the sequence switch to position 5.

In position 5 the fundamental circuit is 55 again closed through the right winding of relay 203, upper right contact of cam 204, upper left contact of cam 205 and thence as previously traced through the stepping relay of the sender to ground. Relay 203 60 operates and locks as before described, clos-

65

ground. Magnet 209 operates and advances the sequence switch to position 3.

In position 3 the circuit of trip magnet 219 is closed from battery through the winding of that magnet, lower right contact of cam 220 to ground. The fundamental circuit is again closed in position 3 through the right winding of relay 203, upper right contact of cam 204, upper left contact of cam 205 and thence to ground through the 70 stepping relay of the sender. Relay 203 operates and locks as before described. It also closes a circuit from battery through the winding of sequence switch magnet 209, upper left contact of cam 216, left front contact of relay 203, lower left contact of cam 208 to ground. Magnet 209 operates and advances the sequence switch to position 4.

In position 4 relay 203 is held operated in 85 its locking circuit which extends from battery through the right winding thereof, upper right contact of cam 211, right front contact of relay 203, upper left contact of cam 204, upper left contact of cam 205 and 90 thence over the fundamental circuit as previously traced. The circuit of high speed updrive magnet 212 is again closed in position 4. Since trip magnet 214 is operated at this time, the selected brush set is tripped 95 and advanced in a group selecting movement. A circuit is momentarily completed from battery through the right winding of relay 203, upper right contact of cam 211, right front contact of relay 203, upper left and lower right contacts of cam 204, commutator strip 217, brush 218, upper left contact of cam 207, left front contact of relay 203, lower left contact of cam 208 to ground 100 each time brush 218 encounters a conducting segment of strip 217. The stepping relay of the sender is intermittently shunted and when this has been done a sufficient number of times the fundamental circuit is opened. When brush 218 engages the next 110 insulating segment in strip 217, the holding circuit of relay 203 is opened and that relay deenergizes. The deenergization of relay 203 opens the circuit of updrive magnet 212, and brings the selector to rest with the 115 brushes engaging the first terminals of the selected group. The release of relay 203 also closes a circuit from battery, winding of sequence switch magnet 209, upper right contact of cam 216, left back contact of relay 203, lower left contact of cam 208 to ground. Magnet 209 operates and advances 120 the sequence switch to position 5.

In position 5 the fundamental circuit is 125 again closed through the right winding of relay 203, upper right contact of cam 204, upper left contact of cam 205 and thence as previously traced through the stepping relay of the sender to ground. Relay 203 operates and locks as before described, clos-

130

ing a circuit from battery through the winding of magnet 209, upper left contact of cam 216, left front contact of relay 203, lower left contact of cam 208 to ground. Magnet 209 operates and advances the sequence switch to position 6. Relay 203 is held operated in position 6 in a circuit extending through the right winding of relay 203, upper right contact of cam 211, right front contact of relay 203, upper left contact of cam 204 and thence as previously traced to ground in the sender.

In position 6 the circuit of low speed up-drive magnet 221 is closed from battery through the winding thereof, upper right contact of cam 207, left front contact of relay 203, lower left contact of cam 208, to ground. The selector switch 250 is advanced at low speed in its units or line selecting movement. A circuit is intermittently completed from battery through the right winding of relay 203, upper right contact of cam 211, right front contact of relay 203, upper left contact of cam 204, lower right contact of cam 205, commutator strip 214, brush 215, upper left contact of cam 207, left front contact of relay 203, lower left contact of cam 208 to ground. This circuit shunts the stepping relay of the sender and when this has taken place a sufficient number of times, the fundamental circuit is opened. When brush 215 engages the next insulating segment of strip 214 the holding circuit of relay 203 is opened and that relay deenergizes. The deenergization of relay 203 opens the circuit of updrive magnet 221, bringing the brush set to rest engaging the terminals of the wanted line. The release of relay 203 closes a circuit from battery through sequence switch magnet 209, upper right contact of cam 216, left back contact of relay 203, lower left contact of cam 208 to ground. Magnet 209 operates and advances the sequence switch to position 9.

When the final selector sequence switch reaches position 6½ a circuit is completed from battery through low resistance 154, lower right contact of cam 155, brush 156, terminal 157, upper contacts of cam 222, winding of relay 223 to ground. Relay 223, operates opening the locking circuit of relay 206 which releases. With relay 206 released, when the final selector sequence switch arrives in position 9, a circuit is completed from battery, through the winding of sequence switch magnet 209, lower right and upper left contacts of cam 210, right back contact of relay 206, to ground. Magnet 209 operates and advances the sequence switch to position 13 without testing whether the called line is busy.

As soon as units selection is completed, ground is connected to conductor 132, and thence over the lower left contact of cam 133, through the winding of incoming se-

lector sequence switch magnet 120, to battery. Magnet 120 operates and advances the incoming selector sequence switch to position 12. When the sequence switch leaves position 11 ground is disconnected from conductor 172 at the lower left contact of cam 171, releasing the sender. If the intercepted operator has seized the trunk and relay 122 is operated, a circuit is completed, in position 12 of the incoming selector sequence switch, extending from battery through the left winding of relay 125, lower left contact of cam 124, upper left contact of cam 123, front contact of relay 122 to ground. Relay 125 is operated and closes a circuit from battery through the winding of sequence switch magnet 120, upper left contact of cam 121, outer front contact of relay 125, lower right contact of cam 130 to ground. Magnet 120 operates and advances the incoming selector sequence switch to position 14. As soon as the sequence switch reaches position 13 a locking circuit is completed for relay 125 from battery through the left winding of that relay, lower left contact of cam 124, lower right contact of cam 123, to ground, thus rendering relay 125 independent of relay 122.

In position 13 of the final selector sequence switch relay 206 is again operated in a circuit extending from battery through the left winding of that relay, upper left contact of cam 220 to ground. Relay 206 operates and, since relay 223 released when the sequence switch left position 8½, locks as before to ground on sleeve brush 147. The operation of relay 206 also closes a circuit from battery through the winding of sequence switch magnet 209, lower contacts of cam 210, right front contact of relay 206 to ground. Magnet 209 operates and advances the final selector sequence switch into position 14. Since relay 203 is not operated at this time a circuit is closed from battery through the winding of magnet 209, upper right contact of cam 216, left back contact of relay 203, lower left contact of cam 208 to ground. Magnet 209 operates and advances the sequence switch to position 15. With the incoming selector sequence switch standing in position 14 and the final selector sequence switch standing in position 15 a talking circuit is completed from the intercepted operator's headset (not shown) associated with cord circuit 115, tip of plug 118 and jack 116, through condenser 117, lower contacts of cam 153, brush 152, terminal 151, upper contacts of cam 205, final selector brush 225, multiple terminal 226 over the called subscriber's line and substation multiple terminal 227, brush 228, upper contacts of cam 229, terminal 157, incoming selector brush 156, upper contact of cam 155, condenser 177, ring of jack 116 and plug 118 to the operator's headset.

The intercepted operator may now listen on the subscriber's line, challenge the line or test the line in whatever manner may be necessary to determine the reason for the 5 repeated busy signal. She will report to the subscriber at substation 100 and will then proceed to disconnect, removing the plugs from jacks 114 and 116. The removal of plug 118 from jack 116 permits the release 10 of relay 122 but a disconnect signal will not be given to the B operator until substation 200 is restored to normal. With relay 122 released, when interrupter 170 closes its upper contact, a circuit is completed from 15 battery through the right winding of relay 158, winding of relay 159 right back contact of relay 158, upper contact of interrupter 170, lower left and upper right contacts of cam 160, back contact of relay 122 20 to ground. Relay 159 operates, but the current flowing through the right winding of relay 158 is not sufficient to cause that relay to operate. Relay 159 in operating connects ground to the left side of the winding 25 of relays 161 and 162.

Under the assumption made that substation 200 was busy on a call incoming from substation 100, battery will be supplied to substation 200 from incoming selector 103. 30 Relays 161 and 162 have a high resistance and are so adjusted as to be very sensitive. They will therefore operate under practically all the current conditions that exist at subscribers' line terminals throughout the 35 establishment of a call, and without causing sufficient current drain to interfere with the establishment of such call or with the progress of conversation. Under the assumed condition a circuit will be completed from 40 battery at selector 103 over brush 163, terminal 164, brush 232, multiple terminal 230, multiple terminal 227, brush 228, upper contacts of cam 229, terminal 157, brush 156, upper left contact of cam 155, winding of 45 relay 162 to ground at the outer right contact of relay 159. Relay 162 operates and closes its left contact. In some cases when a substation is busy with an originating call, with dialing in progress, battery is connected 50 to the tip side of the line, in which case if connection is established thereto from an incoming selector such as 150, relay 161 would be operated. The purpose of having two relays is to insure the operation of this 55 delay means, irrespective of the side of the line to which battery is being supplied. In the case of coin battery, which is sometimes supplied to both sides of the line at once, both relays would operate.

60 When relay 159 operates it also closes a locking circuit for itself extending from battery through the right winding of relay 158, winding of relay 159, left winding of relay 158, left front contact of relay 159, lower 65 left and upper right contacts of cam 160,

back contact of relay 122 to ground. As long as interrupter 170 holds its upper contact closed a portion of the original energizing circuit of relay 159 shunts the left winding of relay 158 and that relay remains 70 deenergized. However, when interrupter 170 opens its upper contact, the current flowing in both windings of relay 158 causes it to attract its armatures. Relay 158 in operating closes a second ground connection 75 to the left terminals of the windings of relays 161 and 162. When interrupter 170 closes its lower contact, a circuit is completed from battery through the right winding of relay 158, front contact of relay 162, 80 (or 161 if that relay had been energized), lower contact of interrupter 170, lower left and upper right contacts of cam 160 to ground at the back contact of relay 122. This circuit shunts the winding of relay 159 85 and that relay deenergizes, but the circuit of relay 162 is maintained from the armature of relay 158. When interrupter 170 opens its lower contact, the circuit of relay 158 is opened and that relay deenergizes, 90 opening the circuit of relay 162. When interrupter 170 again closes its upper contact the circuit previously traced for relay 159 is completed and the cycle of operation just outlined is repeated. 95

When the subscriber at substation 200 restores his receiver and releases the connection over incoming selector 103 and final selector 201, battery is removed from terminal 227 and relay 162 releases. With relay 100 162 released, when interrupter 170 closes its lower contact, the circuit previously traced for relay 158, in shunt of relay 159, is opened at the contacts of relays 161 and 162, and the locking circuit for relays 158 and 159 is 105 maintained. With relays 158 and 159 operated; when interrupter 170 again closes its upper contact, a circuit may be traced from battery through the winding of incoming selector sequence switch magnet 120, lower 110 right contact of cam 121, left front contact of relay 158, upper contact of interrupter 170, lower left and upper right contacts of cam 160, back contact of relay 122 to ground. Magnet 120 operates in this circuit and advances the sequence switch to position 16. When the sequence switch leaves position 14 1/4, relay 125 releases and a circuit is closed from battery through lamp 126, lower left contact of cam 130, outer back contact of 115 relay 125, lower left contact of cam 131, contact of interrupter 165 to ground. A circuit is also completed from battery through lamp 134, lower left and upper right contacts of cam 127, inner back contact of relay 125, left contacts of cam 131, contact of interrupter 165 to ground. Lamps 134 and 126 flash in these circuits until the trunk is returned to normal. The operator observing the flashing of lamps 134 and 126, de- 120 125 130

presses key 166, completing a circuit from battery through the winding of sequence switch 120, lower right contact of cam 133, contact of key 166 to ground. Magnet 120 operates and advances the sequence switch to position 18.

In position 18 a circuit is completed from battery, winding of downdrive magnet 167, lower contact of cam 142, to ground. Under 10 the control of the downdrive magnet, selector switch 150 is restored to normal. Upon reaching normal position, brush 144 encounters commutator segment 168 and a circuit is completed from battery through the winding 15 of sequence switch magnet 120, upper right contact of cam 121, segment 168, brush 144, upper left contact of cam 142 to ground. Magnet 120 operates in this circuit, restores the incoming selector sequence switch to normal and extinguishes lamps 134 and 126.

When the incoming selector sequence switch leaves position 16½ ground is removed from sleeve brush 147 and the circuit of relay 206 is opened. Relay 206 in releasing closes ground to terminal 146 from the upper right contact of cam 224 over the left back contact of relay 206, to hold the trunk busy until the final selector has been restored to normal. The release of relay 206 closes 20 a circuit from battery, through the left winding of relay 203, upper contacts of cam 210, right back contact of relay 206 to ground. Relay 203 operates and closes a circuit from battery through the winding of final selector 25 sequence switch magnet 209, upper left contact of cam 216, left front contact of relay 203, lower left contact of cam 208, to ground. Magnet 209 operates and advances the sequence switch to position 16. Since the subscriber has already restored his receiver to the switch-hook, the circuit of relay 203 is opened when the sequence switch reaches position 16, and that relay releases, closing a circuit from battery through the winding 40 of sequence switch magnet 209, upper right contact of cam 216, left back contact of relay 203, lower left contact of cam 208 to ground. Magnet 209 operates and advances the sequence switch to position 17.

In position 17 a circuit is closed from battery through the winding of sequence switch magnet 209, lower right and upper left contact of cam 210, right back contact of relay 206 to ground. Magnet 209 operates and advances the sequence switch to position 18.

In position 18 the circuit of the downdrive magnet is closed from battery, winding of magnet 236, lower contact of cam 213, upper left contact of cam 207, lower left contact of cam 220, to ground. Under the control of magnet 236, selector 250 is restored to normal whereupon a circuit is closed from battery, through sequence switch magnet 209, lower right contact of cam 216, commutator segment 247 brush 218, lower left contact

of cam 220 to ground. Magnet 209 operates and advances the sequence switch to position 1, whereupon the final selector is in condition for use with other calls.

In case substation 200 had been busy as 70 a called line and the final selector is still connected thereto and awaiting the restoration of the switchhook, conditions are somewhat different. It will be remembered that upon the release of the final selector by the incoming selector, relay 206 deenergizes closing a circuit for relay 203 extending from battery through the left winding of that relay, upper contacts of cam 210, to ground at the right back contact of relay 206. The energization of relay 203 causes the advance of the final selector sequence switch to position 16. Assuming that a final selector similar to selector 250 has been used in the establishment of a normal call, and the line of the called subscriber has not been restored, a circuit will be established in position 15½ extending from battery through the right winding of relay 203, upper contact of cam 211, right front contact of relay 203, lower left and upper right contacts of cam 229, brush 228, terminal 227, over the subscriber's loop back to terminal 226, brush 225, upper right contact of cam 205, lower left contact of cam 204 to ground, which 80 will hold relay 203 energized while the subscriber's receiver remains off the switchhook.

In position 16 battery through resistance 234, over the upper contact of cam 235 is connected in parallel with the winding of relay 203. If the final selector used "no-test" should be connected with a subscriber's line under these circumstances, and the resistance of the line loop is quite low, insufficient current reaches relay 162 to cause it to operate. Relays 158 and 159 remain locked and when interrupter 170 closes its upper contact a second time a circuit is closed for sequence switch magnet 120 extending from battery through the winding of magnet 120, lower right contact of cam 121, right front contact of relay 158, upper contact of interrupter 170, lower left and upper right contacts of cam 160, back contact of relay 122 to ground. Magnet 120 operates in this circuit and advances the incoming selector sequence switch to position 16. When the sequence switch reaches position 14½ a circuit is completed from battery, right winding of relay 125, lower right and upper left contacts of cam 160, lower contacts of cam 158, brush 152, terminal 151, upper contacts of cam 205 of the final selector sequence switch used "no-test" which is standing in talking position, that is, position 15, brush 225, terminal 226, terminal 233, brush 237, and thence over the upper right contact of a cam corresponding to cam 205 and the lower left contact of a cam corresponding to cam 204, belonging to the final selector which is awaiting resto-

ration of the subscriber's switchhook and hence is standing in position 16, to ground. Relay 125 operates, opening the circuits of lamps 134 and 126 and preventing the display of the disconnect signal until the subscriber hangs up, permitting the sequence switch of the final selector which was awaiting release to advance out of position 16.

Upon leaving position 16 ground is disconnected from multiple terminal 226 and the circuit previously traced for relay 125 is opened, whereupon relay 125 releases closing the circuits of lamps 126 and 134 to display the disconnect signal, after which the operation is the same as previously described. If the loop circuit is of sufficiently high resistance, relay 162 will receive enough current to operate and the holding operation will be as is described.

If, when the incoming selector 250 hunts for an idle final selector, which takes place in position 9, there should be none available the selector comes to rest on a set of overflow terminals the sleeve of which is not connected to ground and hence relay 125 releases. The release of relay 125 closes a circuit extending from battery through the winding of sequence switch magnet 120, lower left contact of cam 121, cutter back contact of relay 125, lower right contact of cam 130 to ground. Magnet 120 operates and advances the sequence switch into position 11.

In position 11 a circuit is closed for lamp 134 extending from battery through the left contact of cam 127, contact of interrupter 135 to ground, in which circuit lamp 135 flashes. The operator noting the flashing of lamp 134 alone, depresses the disconnect key 166, closing circuit from battery through the winding of sequence switch magnet 120, lower right contact of cam 133, contact of key 166 to ground. Magnet 120 operates in this circuit and advances the sequence switch to position 14. Meanwhile a signal has been transmitted to the intercepted operator and she will remove plug 118 from jack 116, releasing relay 122. The release of relay 122 initiates the operation of relays 158 and 159 and since no final selector has been seized, and relays 161 and 162 are not operated, as soon as interrupter 170 closes its circuit the second time, the circuit previously traced for magnet 120 is closed and the sequence switch advanced to position 16.

In position 16, since relay 125 is not operated, the circuits of lamps 134 and 126 are closed as before described and both lamps flash after which the operator can depress key 166 and release progresses as previously described. The operator may hold key 166 depressed until both lamps flash, thus avoiding the second depression of the disconnect key.

One of the difficulties which this scheme

is designed to overcome is the destruction of transmission when a final selector used "no-test" is left in position awaiting the restoration of the subscriber's switchhook during the time that a conversation is in progress. This may be pointed out in the drawing of the final selector shown in Fig. 2. In position 16, when the subscriber's receiver is off the switchhook, battery through the right winding of relay 203 and battery through resistance 234, are connected in parallel to the ring side of the subscriber's line, which is the same side to which battery is being supplied from the incoming selector on the completed connection. These batteries would oppose one another and would greatly reduce or possibly destroy transmission. Since with the incoming selector of the present invention it is impossible to advance the final selector used "no-test" until after the subscriber's switchhook has been restored, this difficulty has been entirely overcome.

Another advantage of the present invention lies in the provision of condensers 117 and 177, which prevent the transmission of battery from the intercepted operator's cord circuit to the terminals of the called line which might also interfere with transmission on a call in progress.

Another source of difficulty overcome by the present invention arose in central offices where reversed ringing current for party line ringing was provided by reversing the connection of the line to the multiple terminals in the final selector terminal bank. Under this condition, it was possible for a final selector used "no-test" and one used for a normal call to both arrive at the position of awaiting the release of the called line at the same time but on the terminals of different parties so as to be reversed with respect to one another. This would result in a pair of circuits from the relays 203 of each final selector circuit to ground at 110 the lower left contact of cam 204 of the other circuit independent of the called line, whereupon neither final selector could release until artificially released by an attendant. Preventing the release of the incoming selector used "no-test" until the called line is restored entirely overcomes this difficulty.

What is claimed is:

1. In a telephone exchange system, subscribers' lines, automatic switches for establishing connections between said lines, means for rendering said connected lines non-selectable to said automatic switches, another automatic switch, control circuits therefor, means in said control circuits for establishing connection over said last mentioned automatic switch with a line which has been rendered non-selectable and means for delaying the release of said last men-

tioned automatic switch until said line has been opened.

2. In a telephone exchange system, subscribers' lines, automatic switches for establishing connections between said lines, means for rendering said connected lines non-selectable to said automatic switches, another automatic switch, control circuits therefor, means in said control circuits for establishing connections over said last mentioned automatic switch with a line which has been rendered non-selectable, operator controlled means for releasing said automatic switch and means for preventing the release of said automatic switch until said line has been opened.

3. In a telephone exchange system, subscribers' lines, automatic switches for establishing connections between said lines,

means for rendering said connected lines non-selectable to said automatic switches, another automatic switch, control circuits therefor, means in said control circuits for establishing connections over said last mentioned automatic switch with a line 25 which has been rendered non-selectable, an operator's position, means at said operator's position for releasing said automatic switch, a signal at said operator's position, means responsive to the opening of said subscriber's line for displaying said signal and means for preventing the release of said automatic switch until said signal has been displayed.

In witness whereof, I hereunto subscribe 35 my name this 5th day of February A. D., 1924.

GEORGE THOMPSON.
